COMBINED LOUD-SPEAKER HOUSING AND GRILL

Eberley R. Ethington, Santa Monica, Calif.

Application February 28, 1949, Serial No. 1,132

Term of patent 3½ years

(Cl. D26—14)

To all whom it may concern:

Be it known that I, Eberley R. Ethington, a citizen of the United States and a resident of Santa Monica, California, have invented a new, original, and ornamental Design for a Combined Loud-Speaker Housing and Grill, of which the following is a specification, reference being had to the accompanying drawing, forming part thereof.

Referring to the drawing:

Figure 1 is a top plan view of a combined loud-speaker housing and grill, showing my new design;

Figure 2 is a side elevation of the device as viewed from the underside of Figure 1;

Figure 3 is a side elevation thereof as viewed from the right side of Figure 1; and

Figure 4 is a bottom plan view of the device.

I claim:

The ornamental design for a combined loud-speaker housing and grill, as shown.

EBERLEY ETHINGTON.
